UNITED STATES PATENT OFFICE.

EDWARD J. F. REA, OF HARTFORD, CONNECTICUT, ASSIGNOR TO AMERICAN AUTOMATIC PRESS COMPANY, OF SAN FRANCISCO, CALIFORNIA, A CORPORATION OF CALIFORNIA.

SIDE-REGISTER DEVICE.

1,103,433.

Specification of Letters Patent. Patented July 14, 1915.

Application filed March 18, 1912. Serial No. 684,491.

To all whom it may concern:

Be it known that I, EDWARD J. F. REA, a citizen of the United States, residing at Hartford, in the county of Hartford and State of Connecticut, have invented certain new and useful Improvements in Side-Register Devices, of which the following is a specification.

This invention relates to side-register devices, the object of the invention being to provide a simple and effective apparatus of this character by which a sheet can be accurately and precisely brought against a side-register stop.

The device can be employed with utility in many and widely different connections, although it is of especial advantage when employed in conjunction with or forming part of a printing press. In this particular use the mechanism will grip a sheet of paper about the time it leaves the feed board or equivalent part, and shift said sheet laterally or transversely of the table or similar part of the press or the like and against the side-register stop, by virtue of which said sheet will be fed in true relation to the printing or other mechanism.

In the drawings accompanying and forming part of the present specification I have represented in detail one of the several convenient forms of embodiment of the invention which to enable those skilled in the art to practise the same will be set forth fully in the following description while the novelty of the invention will be included in the claims succeeding said description. From this it will be obvious that I do not restrict myself to said disclosure; I may depart therefrom in several respects within the scope of the invention included in said claims.

Referring to said drawings: Figure 1 is a top plan view of side-register mechanism involving my invention, showing the same incorporated in a printing press only a portion of which, however, is illustrated. Fig. 2 is a transverse section on the line 2—2 of Fig. 1 looking in the direction of the arrow. Fig. 3 is a sectional detail view of mechanism for reciprocating the side-register carriage. Fig. 4 is a detail view of a rocker hereinafter more fully described. Figs. 5 and 6 are sectional views on the lines 5—5 and 6—6 respectively of Fig. 2. Figs. 7 to 12 inclusive are detail views

showing diagrammatically the action of the movable parts of the register mechanism and certain coöperating elements.

Like characters refer to like parts throughout the several figures of the drawings.

As already intimated my improvements can be employed in divers ways, the principal object in view being to take a sheet of any kind and bring it against a relatively fixed stop or abutment, and as I have already observed, the invention is of particular advantage when utilized as part of a printing press, portions of one of which are shown in Figs. 1, 2 and 3. It is immaterial of course with what type of press the register mechanism be employed; the press shown involves in its make-up a table as 15 along which the sheets are fed in any suitable way, although no means is illustrated for this purpose, toward the printing mechanism. (Not shown.) The sheets are fed from a stack or pile down or along a feed board as 16 and approximately at the time each leaves the feed board it is acted upon by the register mechanism to bring one side edge thereof against a side-register stop or abutment. This side-register stop or abutment may vary radically as to character, the principal essential being that a stop or abutment be provided against which the side edge of the sheet can be brought, although the means shown for this purpose will be hereinafter described.

Supported slightly above the table 15 is a suitable carrier as 17 which may as shown, consist of an approximately rectangular plate. The under surface of this plate as shown best in Fig. 2 is not in contact with the upper surface of the table, the two parts being separated or spaced a comparatively short distance which is about equal to the maximum thickness of the sheets to be handled, these sheets as will hereinafter appear passing successively through this space during their travel toward the printing mechanism. Although not essential I have shown as fastened to this plate a substantially angular bracket 18 which is represented as provided at its angle, with a depending lip 19 which constitutes in the present instance the side register stop and against which the sheet is positively moved. In Fig. 1 I have illustrated by an arrow on the feed board 16, the direction of travel of the sheets, and the

- latter in their movement pass through the space between the plate 17 and the table 15, and while in said space they are grasped and are moved against the stop or abutment 19 as will hereinafter more particularly appear. The carrier or plate 17 is adjustable, and owing to the fact that the side register stop is carried by this plate, it will be apparent that the stop itself is also adjustable.
- 10 As a matter of preference, although not of necessity, the adjustment is a double one, there being means for securing a rough adjustment and for also securing a fine or precise adjustment, and these means may vary decidedly as to character, although those shown for the purpose are satisfactory and will now be described. Supported upon the table 15 is a block 20 which has a longitudinal slot 21 disposed as shown, transversely 20 of the press. Extending through this slot 21 is the shank of the winged nut 22, tapped into said table 15. The block 20 is provided with a lateral hub 23 bored to support the micrometer screw 24, and slotted to 25 receive a nut 25 threaded on said screw which is also provided with a check nut 26. The inner end of the micrometer screw 24 is connected with the substantially upright flange of the bracket 18. Rotation of the 30 adjusting nut 25 situated in the slot of the hub 23 causes movement of the screw 24 in the direction of its axis so that when the nut 26 is backed off and the nut 25 is turned the plate 17 and hence the side register stop 19 can be adjusted, and when the adjustment is obtained, the nut 26 will be operated to bring it solidly and firmly against the hub 23 to thereby maintain the adjustment. This, of course, is the micrometer or fine adjustment. The rough adjustment is obtained by shifting the block 20 after the screw 22 is first backed out, and when said block 20 is adjusted, the screw 22 will be set up. Ordinarily the fine adjustment will be all that is requisite, although in some cases it may be necessary to use both, and in this event it is customary to initially make the rough adjustment.
- 35 40 The side-register mechanism preferably but not necessarily includes a carriage, and although this carriage may move in any desirable manner and be supported in any suitable way, it has in the present instance a reciprocatory movement transversely of the table 15, and is provided with gripper means for positively gripping the sheet and moving the same against the side register stop 19. A carriage such as satisfactorily answers my requirements is that denoted in a general way by 28, and this carriage travels in the construction shown in a straight path crosswise of the table 15 being rabbeted in the slot 28' in said table to 45 thus bring the upper face thereof flush with or in the plane of the top of said table, although this is not material. As already stated this carriage has a reciprocatory movement, and any convenient means may be provided for securing this action. The 50 mechanism shown for this purpose will now be described. One of the side rails 29 of the press has an opening for the passage and guidance of the reciprocatory rod 30, said rod being illustrated as fitting in a longitudinal groove 31 in the under side of the carriage 28 being clamped in said groove by the hook or the hook bolt 32, the shank of which extends through a substantially vertically disposed opening in the carriage 28, the nut 33 at the upper end of said bolt, bearing against the relatively stationary supporting member 34 fastened by screws or otherwise to the carriage 28, whereby when the rod is reciprocated, the carriage 55 will partake of a like motion.
- 55 The rod 30 is preferably but not necessarily, reciprocated through the joint action of cam and spring mechanisms, and a cam which answers the requirement is that denoted by 35, said cam being suitably fastened to the power operable shaft 36. Fulcrumed to the framing of the machine between its ends is a lever 37 shown as having at its outer end a T-head 38 to one branch of which the anti-friction roller 39 is connected, and to the other end of which the lower end of the rod 40 is jointed. The cam 35 operates on the lever 37 in such manner as to impart an upward thrust to the rod 40 and thereby through operative connections hereinafter described, advance the rod 30 and therefore the carriage 28, the advancing movement in the present case being inward or toward the left in Figs. 1 and 2. The retractive movement of the rod 40 and thereby of the carriage 28 and other parts may be accomplished by a spring as 41 acting against the inner branch of the lever 37 the motion of which is limited by an adjustable stop 42 which may as shown consist of a screw tapped into some suitable part of the framing of the machine.
- 45 50 The connection between the rods 40 and 30 or equivalent mechanism, is preferably 55 accomplished by means which permit an adjustment whereby the side-register carriage 28 may be advanced from initially either side of the press and naturally the means for securing this particular object may differ. For this purpose I have shown the rocker 43 which is practically a three-armed lever pivoted to the bracket 45 on the framing of the machine, the rod 30 being pivotally connected with said rocker or three-armed 60 lever at one point (below its center of motion in the construction shown), while the rod 40 is adapted to be adjustably connected with said rocker at other points (above said center), whereby I can obtain the reversal 65

to which I have alluded, and I might also add that the rod 40 is so related with the rocker 43 or analogous members that the degree of movement of the carriage may be regulated. The upper end of the rod 40 has an opening to freely receive the bushing 44 which constitutes a convenient means for pivotally connecting said rod with the rocker. Through the bushing the bolt 46 extends, the nut 46' of the bolt being adapted to engage against a collar on the outer side of the bushing 44 and the inner end of said bushing bearing against the face of the rocker 43. This bolt 46 extends through a T-slot 47 arranged on an arc along the upper side of the rocker 43, the head 48 of said bolt being in the wide portion of said T-slot 47. When the head 48 binds against the forward wall of the wide portion of the slot the rod 40 will be held in adjusted relation, but by loosening the nut 46' the upper end of the rod can be adjusted in an arc to secure the functions set forth. The head 48 is shown in Fig. 3 at one end of the T-slot 47, and when this adjustment is present, the carriage 28 will on the motion of the rod 40 be initially advanced from the position shown in Figs. 1 and 2, while if the rod 40 be shifted to the other side of the arcuate portion of the rocker 43, the carriage can be initially advanced from the other side of the press, it being essential, however, in the latter event to reverse the position of the carriage 28 and to also move it along the rod 30. By moving the connection between the rod 40 and the rocker 43 nearer the vertical center line, the degree of movement of the carriage can be decreased.

The top of the carriage 28 practically forms a relatively-fixed jaw being coöperative with a movable jaw or gripper which is made in the form in the present instance, of a pivotally mounted finger or lever 49 carried between its ends by the forked bearing 50 on the support 34 to which I have already referred. The active portion of this gripper or finger 49 is preferably resilient or yieldable in its nature, and this quality can be properly secured in any desired manner for example by a rubber pad as 51 which is shown as cylindrical in form and adapted to snugly fit a correspondingly-shaped opening or seat in the inner end of the gripper member or finger 49 that part of the pad 51 which directly engages the sheet of paper or other material being preferably, but not necessarily, convex so as to eliminate the possibility of suction between the pad and sheet and to also reduce to the least possible extent the contact.

The finger 49 is provided at its outer end with the pendent member 60 loosely pivoted thereto as shown in Figs. 2 and 6, and this member in the present instance is operated

upon by cam means as I will hereinafter point out, spring means being provided as will now appear to constantly impart an upward thrust to said element 60 and thereby operate the same in opposition to said cam means. The part 60 is shown provided with a lateral lug or extension 61 into which the screw 62 is tapped, said screw having a plain downward extension 63 encircled by the coiled spring 64 fitting partially in the socket 65 in the carriage 28 as shown best in Fig. 6, one end of the spring engaging the bottom of the socket, while the other end thereof bears against the lower end of the screw 62, said spring as will be evident exerting a constant force against the part 60 to thrust the same and thereby the outer branch of the oscillatory finger 49 upward and necessarily the inner branch of said finger downward. By the operation of the screw 62, the tension of the spring 64 can be regulated.

The member 60 extends into an aperture or slot 66 in the carriage 28 shown in said Fig. 6 and between said member 60 and the opposite wall of said slot 66 are arranged the two plates 67 and 68, these plates being disposed as will be clear, side by side, and accidental movement thereof being prevented in some suitable manner as by the spring-operated shoe 69 fitted in the chamber 70 of the supporting-member 34, (Fig. 5), said shoe engaging at all times the upper edges of the two plates 67 and 68 to prevent such accidental movement. The pendent member 60 is provided with an offset 71 directly cooperative with the two plates 67 and 68. The two plates 67 and 68 are operated relatively to the carriage 28 on the movement of the latter to effect the required action of the finger 49, and such result is secured in the present case by holding said plates against movement with respect to the carriage, and any suitable means may be provided for this purpose for instance the yoke 72, the shank 73 of which has a hub 74 adjustable on the stationary shaft 75, said hub being held normally in adjusted position on said shaft by the set screw 76. As the carriage 28 travels back and forth, this yoke operates the two plates 67 and 68 in proper order, directly governing the plate 68 and through the latter the companion plate 67, said plate 68 being provided for such purpose with an upwardly-extending projection 77 at the outer end thereof situated between the two branches of the yoke 72. The main plate 68 has on its inner side a rabbet 78 to receive the complementary plate 67, the end walls of the said rabbet 78 serving to operate the plate 67 at desired times to effect the necessary operation. The main plate 68 has in its lower edge the slot 79 the outer wall of which is made as a cam face being on a slant or incline as shown at 80, said plate 130

thus constituting a cam. The auxiliary plate 67 is provided with a release or let-off notch or slot 81 in its lower edge. The upper side of the offset 71 is shown having a 5 beveled face 82 on an angle agreeing with the cam wall of the slot 79.

In Fig. 7 the parts are shown as occupying their primary relations at which time the carriage 28 (not shown in this or the 10 succeeding five views) will be in its retracted position, while the projection 77 will be against the outer branch of the yoke 72, and the upper side of the offset 71 will be against the lower edge of the cam 68 by reason of 15 which the active end of the finger 49 or that provided with the pad 51 will be held elevated by the spring 64 in the manner already described. The lower edge of the controlling member or plate 67 will also be 20 against the upper side of the offset 71 and thereby also tend to maintain said pad elevated. As the carriage 28 advances or moves toward the left in said Fig. 7, the projection 77 will be carried away from the 25 outer and toward the inner branch of the yoke 72 but the relation of the parts will not vary as shown in Fig. 8, the projection 77 just having engaged the inner branch of said yoke in this figure. It will be clear that 30 as the carriage advances the plates 67 and 68 are moved therewith by the spring shoe 69. When the projection 77 strikes the inner branch of the yoke 72 as illustrated in Fig. 8, the movement of the cam 68 with the 35 carriage is thereby arrested, so that on the continued advancing movement of the carriage said cam 68 will be operated relatively to the carriage. On the further advance of the carriage the cam or plate 67 is carried 40 therewith as shown in Figs. 9 and 10 to thereby gradually bring the two slots 79 and 81 into register as shown in the last mentioned figure. During this last mentioned movement the active or inner end of 45 the finger 49 will be slowly lowered by the spring 64 to bring the pad 51 into contact with the paper, this occurring at about the time the carriage reaches the limit of its inward movement, by virtue of which the 50 sheet is gripped between the pad and the carriage, the pad being compressed. When the sheet is thus gripped the reverse or retractive action of the carriage follows, and on the outward movement of the carriage 55 the plates 67 and 68 are carried therewith until the projection 77 strikes the outer branch of the yoke 72 as shown in Fig. 11, this action occurring practically at the time the paper is against the side register stop 60 19. On the continued and slight further movement outwardly of the carriage 28, the plate 68 is operated relatively by the outer branch of the yoke 72 engaging the projection 77 so as to raise the pad 51, the pad during the last mentioned stage of its action or

from the time the paper reaches the side register stop and until the pad and carriage reach their initial positions traveling in an upward, outward angular path. I say "practically" as the pad does not exactly 70 travel along a straight line, initially following somewhat a curved line until the effect of its resiliency against the paper is expended, by reason of which the paper is placed positively against the side register 75 stop with the precision and accuracy of the human hand.

It will, therefore, be apparent that my apparatus comprises a movable body which has been described hereinbefore as a carriage movable in a straight path, although as will be gathered from the observations already made, this is not essential. This moving or traveling body or carriage is furnished with a movable jaw which in the construction set forth consists of the gripper member or finger 49 and which cooperates with a relatively fixed jaw made up preferably but not necessarily of the upper portion of said traveling carriage or body. It 85 will be also clear that I provide mechanism for causing the relatively closing and opening movements of said jaws at different points in the travel of the body, so that the jaw mechanism can grip a sheet and then 90 release the same at about the time said sheet is against the side register stop 19 or equivalent member.

I desire to call attention to the fact that the traveling carriage or body 28 is provided 100 with a side gage, and although this may consist of any suitable part it is shown as being the inner straight flanged edge 34' of the supporting member 34 to which I have already referred and which, it will be remembered, is rigid with said carriage. This side gage or straight edge 34" in addition to straightening out the sheet also serves to bring the same in definite relation with the active end, which as shown is the pad 105 51, of the gripper member, jaw or finger 50, so that notwithstanding the fact that the sheets may vary in size, this relation will be thereby always assured to thus aid in insuring accuracy in printing.

I desire to again call attention to the fact that I have simply illustrated and described one of the many organizations which I have found highly advantageous, and each of which embodies the invention. I wish to 110 make it clear that I do not limit myself to this particular disclosure, the invention residing in certain broad relations which will be included in my claims.

What I claim is:

1. The combination of a reciprocatory carriage, a gripper member on said carriage, a pair of plates on the carriage, having releasing notches for the gripper member, means for causing the movement of said 120 130

plates with said carriage, means for arresting the movement of one of the plates with the carriage whereby the other can be moved with the carriage to effect registration of the 5 notches to thereby release the gripper member, and means for shifting the gripper member when thus released.

2. The combination of a reciprocatory carriage, a gripper member on said carriage, a 10 pair of plates on the carriage, having releasing notches for the gripper member, means for causing the movement of said plates with said carriage, means for arresting the movement of one of the plates with the carriage 15 whereby the other can be moved with the carriage to effect registration of the notches to thereby release the gripper member, and means for shifting the gripper member when thus released, one of the plates having means 20 for positively operating the gripper member.

3. The combination of a reciprocatory carriage, a gripper member on said carriage, a pair of cam members supported by 25 the carriage for movement therewith, said cam members being adapted to govern the gripper member, means supported independently of the carriage for effecting relatively the movement of one of the cam members to 30 releasing position, the carriage on its movement conducting the other cam member to a position where it can coöperate with the companion cam member to effect the release of the gripper member, and means for causing the gripper member to move toward the carriage when the two cam members release 35 the gripper member.

4. The combination of a reciprocatory carriage, a gripper member on said carriage, a 40 pair of slideable cams supported by the carriage for movement therewith and adapted to normally hold the gripper member against movement, each cam having a releasing notch, means independent of the carriage for 45 arresting the movement of one of the cams with the carriage whereby the notch of the other cam can be carried into register by the carriage with the notch of the arrested cam to release the gripper member, and means 50 for operating the gripper member when the notches are in register.

5. The combination of a reciprocatory carriage, a gripper member on said carriage, a main cam having a releasing notch, an auxiliary cam also having a releasing notch, 55

means on the carriage for effecting the movement of the cams therewith, a stationary part supported independently of the carriage for arresting the movement of the main cam with the carriage, the auxiliary 60 cam being carried with the carriage on the arrest of movement of the main cam to bring the notches into register and thereby release the gripper member, and means for imparting an operative movement to the 65 gripper member when it is thus released.

6. The combination of a reciprocatory carriage, a gripper member on said carriage, a main cam having a releasing notch, an auxiliary cam also having a releasing notch, 70 means on the carriage for effecting the movement of the cams therewith, a stationary part supported independently of the carriage for arresting the movement of the main cam with the carriage, the auxiliary 75 cam being carried with the carriage on the arrest of movement of the main cam to bring the notches into register and thereby release the gripper member, and means for imparting an operative movement to the 80 gripper member when it is thus released, the notch of the main cam having means for positively moving the gripper member toward releasing position.

7. The combination of a reciprocatory carriage, a gripper member on the carriage, a main cam provided with a projection and having a rabbet, an auxiliary cam fitted in said rabbet, both cams having releasing notches, means on the carriage for effecting 85 the movement of the two cams therewith, a yoke supported independently of the carriage, one branch of the yoke being adapted to arrest the movement of the main cam with the carriage on the advancing movement of 90 the latter, and the other being adapted to return said main cam to its primary position on the opposite movement of said carriage, the auxiliary cam being carried with the carriage when the main cam is arrested to 95 effect registration of said notches, and means for imparting a working movement to the gripper member when the notches are in 100 register.

In testimony whereof I affix my signature 105 in presence of two witnesses.

EDWARD J. F. REA.
